UNITED STATES PATENT OFFICE.

ARTHUR C. LANG, OF CHICAGO, ILLINOIS, ASSIGNOR TO THE N. K. FAIRBANK COMPANY, OF CHICAGO, ILLINOIS, A CORPORATION OF NEW JERSEY.

DESIGN FOR A CAKE OF SOAP.

58,032.

Specification for Design.

Patented May 31, 1921.

Application filed May 20, 1920. Serial No. 382,989. Term of patent 14 years.

To all whom it may concern:

Be it known that I, ARTHUR C. LANG, a citizen of the United States, residing at Chicago, in the county of Cook and State of Illinois, have invented a new, original, and ornamental Design for a Cake of Soap, of which the following is a specification, reference being had to the accompanying drawing, forming part thereof.

Figure 1 is a perspective view of my improved cake of soap.

Fig. 2 is a side elevation of the same.

Fig. 3 is a fragmentary transverse sectional view of the same.

I claim:

The ornamental design for a cake of soap as shown.

ARTHUR C. LANG.
